United States Patent Office.

CHARLES F. HARLOW, OF BOSTON, MASSACHUSETTS, ASSIGNOR TO HIMSELF
AND DEXTER S. KING.

Letters Patent No. 79,468, dated June 30. 1868.

IMPROVED MACHINE FOR CUTTING AND TRIMMING BRISTLES, FELT, FUR, WOOL, &c.

The Schedule referred to in these Letters Patent and making part of the same.

TO ALL WHOM IT MAY CONCERN:

Be it known that I, CHARLES F. HARLOW, of Boston, in the county of Suffolk, and State of Massachusetts, have invented certain new and useful Improvements in "Brush-Shearing Machines;" and I do hereby declare that the following is a full, clear, and exact description thereof, reference being had to the accompanying drawings, and the letters of reference marked thereon.

In the annexed drawings, making a part of this specification—

Figure 1 represents a side view.

Figure 2 represents a side view of cutter and movable bar.

Figure 3 represents a plan view of my machine, with one end cut away.

Figure 4 represents a section of the movable bar and cutter.

Figure 5 represents a bottom view of the screw and worm-gear for operating the feed-shaft.

The nature of my invention consists in constructing a machine to enable the operator to trim or shear bristles, wool, fur, felt, silk, or other fibrous and flexible material to a uniform length, and give the same a smooth and even surface.

To enable others skilled in the art to make and use my machine, I will proceed to describe the same.

In the annexed drawings, A represents the table or bench, on and under which the different parts of my machine are secured and work, and B represents the stand or base supporting the table and machine.

C C represent the upright framework, and D the horizontal part of the framework supporting the cutters g g, and movable or sliding plate E.

Adjusted and working up and down on the uprights C C, are curved or bent horizontal bars X X, said bars being secured at any elevation desired by means of suitable set-screws.

These horizontal bars afford a support to the material to be cut or sheared, and furnish a gauge so that the material may be cut of any length desired.

F represents a vertical column or shaft, which supports the feed-shaft p, by means of a suitable slotted arm, as shown.

p represents a shaft, provided with a series of teeth or knobs, having bearings in slots in the table A, and the arm of the column F. The shaft p is held steady in its bearings, and so as to give the pressure by means of the springs q q, so as to conform to the thickness of the back of the brush, and, by means of its teeth or projections, to slide the same along behind the horizontal bars X X, and thereby feed the bristles projecting between said bars up to the cutters g g.

Secured to the lower end of the feed-shaft p, beneath the table A, is a worm-gear, o, which meshes with the screw or worm n, on the shaft m.

b represents a shaft, adjusted horizontally on the table A, and has the driving-pulley a attached to one end of it, and a crank or eccentric-pin projecting from the other end, by which the movable cutter or shear g is operated up and down by means of the connecting-link C and slide E.

The shaft b has another pulley, K, attached to it, which is connected by a band to a pulley, l, on one end of the shaft m, and thereby operates said shaft with its worm or screw n.

The slide E works up and down in and against a suitable vertical way or guide, S, to which one of the cutters or shears g is secured.

The horizontal part of the frame D is provided with a slotted arm, as shown in fig. 3, in which the top of the guide S is secured, the bottom of said guide being secured to a movable table, R.

The table R rests and works on a track or tongue on the main table A, and is secured thereto by means of screws and bolts, which work in suitable slots in the table A. The table R is made adjustable, so that the cutters g g and guide S may be set or gauged at any desired distance from the jaws or horizontal bars X X, to correspond with the length it is desired to cut the bristles or material of the brush.

To use my machine, the operator first adjusts the untrimmed brush between the jaws or bars X X, with the back of said brush between said jaws and the feed-shaft *p*. The table R, with the cutters *g g* and guide S, is then adjusted as desired, and then power applied to the drive-pulley *a*, which operates the shaft *b*, pulley K, and the crank or eccentric-pin, and thereby the link C, slide E, and one of the cutters *g*. The pulley K, by means of a suitable band, operates at the same time the pulley *l* and its shaft, *m*, with the worm or screw *n*, which in turn operates the feed-shaft *p* by means of the gear *o*.

It will thus be seen that the brush is automatically fed or moved up to the cutters *g g*, and trimmed or sheared neatly thereby.

Having thus fully described my invention, what I claim as new, and desire to secure by Letters Patent, is—

1. The combination of the stationary toothed knife *g* and movable toothed knife *g*, with the guide S and slide E, when constructed to operate as set forth.
2. The combination of the sliding table R, guide S, slide and cutters *g g*, with the slotted arm of the beam D and table A, for the purpose of adjusting the cutters *g g* at any desired distance from the jaws or bars X X, as specified.
3. The feed-shaft *p*, adjusted in the slotted bars, and held by the springs *q*, in combination with the cutters *g g*, arranged upon the sliding table R, to operate substantially as set forth.
4. The curved or bent horizontal bars X X, when made adjustable on the posts C C, and arranged as and for the purpose specified.

CHARLES F. HARLOW.
